UNITED STATES PATENT OFFICE.

PETER KREBITZ, OF MUNICH, GERMANY.

PROCESS FOR RECOVERING THE RESIDUAL SOAP FROM CARBONATE-OF-LIME SLUDGE.

No Drawing. Original application filed June 15, 1921, Serial No. 477,787. Divided and this application filed November 16, 1922. Serial No. 601,391.

To all whom it may concern:

Be it known that I, PETER KREBITZ, a citizen of Germany, residing at Munich, Germany, have invented certain new and useful

5 Improvements in the Processes for Recovering the Residual Soap from Carbonate-of-Lime Sludge, of which the following is a specification.

My invention relates to an improved process for recovering the residual soap from carbonate of lime sludge, and the present application constitutes a division of my co-pending application Serial Number 477,787, filed June 15, 1921.

15 In the manufacture of soap, it was heretofore impossible to recover the total residual soap from the carbonate of lime sludge, unless the original soap mixture contained no less than twenty-five per cent of

20 cocoa-nut oil or palm-seed oil; and in cases where certain kinds of fat, such as animal fats, hardened fish-oil and others, were used in the original soap mixture, such recovery was not possible even if twenty-five per cent

25 or more of cocoa-nut oil or palm-seed oil constituted a part of the original mixture.

The object of my invention is to provide an economical process for the recovery of the entire residual soap in the carbonate of lime sludge, and I accomplish this object by adding to the sludge from one to six per cent of resin soap, so that the entire soap content of the sludge shall consist of at least twenty per cent of saponified resin.

35 My improved process may advantageously be carried out as follows:—To 4500 parts

by weight of lime sludge resulting from treating palm-oil lime soap with soda solution add 150 parts by weight of saponified resin and water until sufficient for elution 40 of the carbonate of lime, thoroughly agitate the mixture, or boil it for a short time and permit it to settle. After settling a clear soap solution will separate out and rise to the top, and may be removed. 45

The carbonate of lime sludge contains from three to fifteen per cent of residual soap, dependent on the character of the original soap making material, and the essential feature of my invention consists in 50 adding to this sludge between one and six per cent of resin soap, so that the entire soap content of the sludge will consist of at least twenty per cent of saponified resin. By this addition of from one to six per 55 cent of resin soap to the sludge the soap mixture of the sludge is so modified that it contains at least twenty per cent of saponified resin whereby complete removal of residual soap from the sludge is made possible. 60

I claim:—

In the herein described process of recovering residual soap from carbonate of lime sludge, the step which consists in adding to 65 the sludge a sufficient quantity of resin soap so that the entire soap content of the sludge will consist of at least twenty per cent of saponified resin.

In testimony whereof I have affixed my 70 signature.

PETER KREBITZ.
